UNITED STATES PATENT OFFICE.

FLOYD B. GROFF AND FAYETTE GROFF, OF ST. JOHNSVILLE, NEW YORK.

HORSESHOE.

1,195,210.

Specification of Letters Patent. Patented Aug. 22, 1916.

Application filed June 9, 1913. Serial No. 772,608.

To all whom it may concern:

Be it known that we, FLOYD B. GROFF and FAYETTE GROFF, citizens of the United States, residing at St. Johnsville, in the county of Montgomery and State of New York, have invented certain new and useful Improvements in Horseshoes, of which the following is a specification.

This invention has relation to new and useful improvements in horse shoes and especially to detachable calks thereof.

The main object of the invention is to produce a horse shoe that may be utilized or employed in both good and bad weather, by the non-use or employment of detachable calks.

A further object of our invention is to produce a shoe that will save expense to the owner, in that it is unnecessary to reshoe a horse, using our improved shoes, at the change of seasons, as is now generally the custom.

A further object of our invention is to produce a shoe that will prevent undue injury to a horse's hoofs, due to reshoeing them too often, made necessary by the employment of the old style of shoes now in use.

The invention therefore consists of certain structural features relating more especially to the heel and toe calks and their combination and arrangement with the shoe, substantially as hereinafter fully disclosed and defined by the appended claim.

In the accompanying drawing is illustrated the preferred embodiment of our invention wherein it will be understood that various changes and modifications may be made as to the detailed construction and arrangements of the parts without departing from the spirit of the invention and in which drawing

Figure 1, is an inverted plan view of our horse shoe. Figs. 2 and 3 are fragmental sectional views showing a toe-calk and heel-calk, respectively. Figs. 4 and 5 are separate or detached perspective views of a toe-calk and a heel-calk, respectively. Fig. 6 is a vertical section of a modification of the calks.

In carrying out our invention, we equip the horse-shoe 1, with detachable or removable heel and toe calks, the toe calk being designated as 2, and the heel calks as 3, these

calks each being provided at the upper or 55 attaching end with a plurality of steps, as 4 and 4^a, the intermediate step 4^a having also upwardly and outwardly flared longitudinal or forward and rearward walls as at 4^b, said intermediate step being dove-tailed in general outline, to guard against vertical displacement or detachment. The shoe 1 is provided with sockets or recesses 5 in its lower surface, of conforming outline with that of the upper ends of the calks, 60 said sockets or recesses of course being designed to receive said calk upper ends and opening laterally for the suitable insertion or attachment of the calks to the horse shoe, the lateral entrances for the toe-calks being 70 designated as 5^a.

The central top or uppermost step 4^c of each calk, which has right lined lateral and top walls, serves to centralize the positioning of the calks within their sockets, said 75 top-step it will also be observed is of such cross-section that as it is hammered or driven endwise into position in its receiving groove it will serve as a key by exerting downward pressure upon and thus wedging 80 the other steps of the calk into locked down position in their receiving sockets.

This form or construction of calk, it is apparent, is readily displaceable, thus providing for the detachment or removal of the 85 calks when the use of the same may not be required or necessary. Also the calks are readily or quickly applied to the horse-shoe when required for use, as in sleety or icy weather, all being effected without the use 90 of additional or separate fastening, or resorting to the services of a blacksmith.

In the modification as suggested by Fig. 6, is shown a form of calk, as 7, itself employing a removable central step-forming 95 member 8 inserted within a central orifice, or between half-calk-forming members or sections and adapted by reason of its outline to bind against the opposed walls of said sectional-calk-members, and whereby the 100 manufacture or making of the calks is thought to be expedited, said calks being capable of being produced of scrap or waste pieces of metal.

What we claim is:

A horse-shoe equipped with heel and toe calks, said calks having stepped formations at their upper ends, said stepped forma-

tions, each forming a dovetailed tenon, itself extended into a relatively reduced rectangular top step, said horse-shoe being provided with corresponding sockets for the reception of said dovetailed tenons and their rectangular extensions or steps, said top steps being adapted to be driven into place and providing for the retention of said calks in place.

In testimony whereof we affix our signatures in presence of two witnesses.

FLOYD B. GROFF.
FAYETTE GROFF.

Witnesses:

L. BERKMAN,
A. E. STORMS.
